(57) **CLAIM**

The ornamental design for a wireless headphone, as shown and described.

DESCRIPTION

FIG. 1 is a front perspective view of a wireless headphone, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a partial enlarged view of FIG. 2; and,

FIG. 9 is a partial enlarged view of FIG. 4.

The broken lines in the drawings illustrate the portions of the wireless headphone, which form no part of the claimed design.

The dot dash broken lines encircling portions of the wireless headphone in FIGS. 2 and 4 and illustrated in the enlarged views of FIGS. 8 and 9 form no part of the claimed design.

1 Claim, 9 Drawing Sheets(56)
